[57] CLAIM

The ornamental design for a wall mounted recessed dryer, as shown and described.

DESCRIPTION

FIG. 1 is a perspective view of the wall mounted recessed dryer showing my new design;

FIG. 2 is a side elevation view thereof;

FIG. 3 is a bottom plan view thereof;

FIG. 4 is a rear elevation view thereof;

FIG. 5 is top plan view thereof;

FIG. 6 is a perspective view of a wall mounted recessed dryer showing a second embodiment of our new design, the sole difference being in the omission of a start button;

FIG. 7 is a bottom plan view of the second embodiment shown in FIG. 6.

FIG. 1.

FIG. 3.

FIG. 2.

FIG. 4.

FIG. 5.

FIG. 6.

FIG. 7.
